FURNACE HEAT EXCHANGER

William R. Teller, Cleveland, Ohio, assignor, by
mesne assignments, to Affiliated Gas Equipment,
Inc., Cleveland, Ohio, a corporation of
Delaware

Application November 27, 1946, Serial No. 712,485

1 Claim. (Cl. 257—245)

1

This invention relates to sheet-metal heat-exchanger tubes for welded assembly with similar tube units in a battery; the battery being particularly intended for employment to transfer heat from high temperature products of combustion, to forced air to be heated for comfort; as for example in a gas-fired forced air furnace or unit heater.

Objects of the invention are to provide, in such a tube, a minimum joint to be welded, a form and location facilitating the necessary welding, and optimum joint location in subsequent service.

Another object is to attain the same desiderata, as applied to the battery assembly of the tubes.

Still another object is to provide a battery as well as tube form therefor, capable of serving in the furnace or the like, as an integral structural part thereof as will appear.

Further objects and advantages will be apparent from the following description taken in connection with the accompanying drawings, wherein

Fig. 1 is a perspective view of a tube unit embodying the invention,

Fig. 2 is a sectional elevation intermediate the ends of the tube shown in Fig. 1,

Fig. 3 is a perspective view of a battery of such units, and

Fig. 4 is a perspective view of pertinent parts of a forced air furnace in which such a battery is incorporated, nearby parts being omitted to show details of construction.

In the drawings the indicated tube disposition is that providing horizontal passage therethrough, and hereinafter terminology will imply such disposition. However, this is primarily for convenience and to avoid confusion; and it will be understood that, while such disposition is preferable in some instances as will appear, the invention is in nowise limited thereto.

With reference now to the drawings and first to Figs. 1 and 2 thereof, the tube is formed of a single, generally rectangular piece of sheet metal generally bent upwardly on either side of its transverse midsection so that the tube provides a horizontal passageway of much greater height than width, is seamless at its bottom and has a longitudinal seam along its top.

The tube is formed to have rectangular section at end portions as appears in Fig. 1, each end portion including a pair of flat side members 1, a single flat bottom member 2, and a pair of flat top member 3, meeting each other edge to edge. These members, at each end of the tube may be

2

co-extensive longitudinally thereof. However, preferably at each tube end, one of the flat side members 1 extends outwardly slightly beyond its corresponding members to facilitate welding of the tube in its battery, as will appear hereinafter.

Longitudinally intermediate these rectangular end portions, the tube is of somewhat lesser width and is contoured to provide curved corners as indicated. At its top the tube has its longitudinal seam provided by upstanding flanges 5 extending between and terminating at the rectangular end portions of the tube. Preferably, one of the flanges 5 extends up slightly beyond the other two, thus forming a slight groove 6 between the flanges to facilitate welding therealong, the welding contemplated providing a fillet of added metal in and along such groove as in the shielded arc method.

For improving heat transfer while permitting cleaning and avoiding noise, as will appear, the tube may be provided on each side with one or more vertically spaced series of boss deformations 7, these deformations terminating in planes slightly within the planes of the corresponding side edge members 1 of the rectangular end portions of the tube as appears in Fig. 2.

To form the heat exchanger battery, a plurality of tubes is placed in side by side relation as indicated in Fig. 3.

In such relation, adjacent side members 1 at the end portions of each adjacent pair of tubes are interconnected by welding as at 8 along their vertically extending outer extremities. These welding operations are facilitated by the grooves 6 formed along such extremities by the extension of one edge beyond the other, of each pair of side members 1 to be welded together in the same manner as described in connection with the grooves 6 at the longitudinal seams of the individual tubes.

It will be apparent that the battery thus formed will provide, besides the horizontal flow path along and through each tube, a vertical flow path between each adjacent pair of tubes, of less width than the horizontal paths, and into which the bosses 7 project, the bosses of adjacent tubes slightly clearing each other.

It will also be apparent that the battery is of generally rectangular form about the aggregate of both its horizontal and vertical series of flow paths. More particularly at each of its aggregate horizontal flow path ends the battery effectively has a peripheral flange formed at the top by the corresponding flat top members 3 of its tube end portions, at the bottom by the flat bottom mem-

bers 2 thereof and at its lateral extremities by the far flat side members 1 thereof.

With reference now to Fig. 4, the battery may be assembled as an integral part of a furnace or the like by incorporation with confining or closure means, and including panel means adjacent corresponding ends of a series of flow paths, with flange means overlaid on the corresponding adjacent end flange portions of the battery.

Thus as in Fig. 4, at the bottom of the battery where the closure means may bound a combustion chamber to enclose a burner 14 or other source of heat, panel members 9 may be provided, having flanges 10 extending along and engaging the corresponding adjacent end flange portions 2 of the tubes of the battery. Similarly at the top of the battery, to provide a flue passage leading therefrom, panel members 11 may be provided with flanges 12 overlaid on the corresponding adjacent end flange portions 3 of the several tubes, the upstanding flanges 5 of the longitudinal tube seams fitting between the panel members 11 as indicated.

At the ends of the battery, adjacent the end tubes thereof, means such as the panel member 13 are provided for closure to complete the combustion chamber below the battery, and the flue passage above the battery. As will be appreciated, each closure panel member 13, of which only the far one appears in Fig. 4, has suitable connections with the panel members 9 and 11, and the corresponding near pair of flat side members 1 of its near tube, so as to provide a vertical flow path from the combustion chamber to the flue passage, bounded on one side by the panel member 13 and near side of the near tube, such vertical flow path being half the effective width of the typical vertical flow path between adjacent tubes of the battery.

The parts are interconnected by welding to preserve their described assembled relation. Such welding includes, in horizontal planes, at the bottom of the battery welds along the adjacent ends of the flanges 10 and 2, and at the top of the battery along adjacent extremities of flanges 12 and 3. Here also, if desired, to facilitate welding the parts may be so proportioned that the continuous flanges 10 and 12 extend slightly beyond their corresponding tube flanges 2 and 3 respectively, generally as already described in connection with the grooves 6 and 8.

The end panels 13, besides having interconnection with the panels 9 and 11 in a convenient manner, have edge welded connection along the extremities of the adjacent flat side members 1 of their end tubes of the battery.

It will be observed that to provide the described completed furnace assembly all of the welding necessary is along an easily accessible pair of

straight sheet metal edges, so that it is easily accomplished and the resultant joint easily inspected. Particularly no welds are exposed to direct heat from the burner 14 or other source of high temperature within the combustion chamber; exposed parts of the individual tubes there being seamless. The seams 6 at the tops of the tubes are exposed only to the relatively low flue-gas temperatures at that location. The remaining welds are exposed only to temperatures greatly therebelow, it being understood that in practice, means not illustrated are provided for forcing air to be heated through the horizontal flow paths of the battery.

What I claim is:

Apparatus of the class described comprising a sheet metal heat exchanger battery, of tubes in horizontally extending side-by-side disposition, each tube having rectangular form at each end thereof, provided by end flange means extending peripherally about the mouth of the tube, with four rectangularly related end flange portions disposed in planes longitudinal of the tube, each tube having curved top and bottom portions longitudinally extending between its said end flange means and being of less width between than at said end flange means, each tube being seamless along its bottom, and having a seam along its top formed with upturned flanges of rectangular outline, extending between, terminating at, and upstanding beyond its said end flange means, said upturned flanges being welded together along their upper extremities, and closure means for said battery, disposed at an upper end thereof crosswise of the tubes thereof, said closure means having an outturned flange overlying the corresponding uppermost end flange portions of the tubes of the battery and welded to the latter at their endwise extremities, and said closure means including a face panel portion upstanding from its said outturned flange and bearing against the corresponding ends of the upturned flanges of said seams of said tubes.
